(57) **CLAIM**

The ornamental design for a coupler for coupling a camera to an endoscope, as shown and described.

DESCRIPTION

FIG. 1 is a side elevational view of a coupler for coupling a camera to an endoscope, showing our new design.

FIG. 2 is a side elevational view of the coupler, showing the opposite side from FIG. 1.

FIG. 3 is a top elevational view of the coupler.

FIG. 4 is a bottom elevational view of the coupler.

FIG. 5 is a distal end elevational view of the coupler.

FIG. 6 is a proximal end elevational view of the coupler.

FIG. 7 is a distal perspective view of the coupler, shown coupled to a camera and an endoscope.

FIG. 8 is a distal perspective view of the coupler, from the opposite side shown in FIG. 7, shown coupled to a camera and an endoscope.

FIG. 9 is a proximal perspective view of the coupler, shown coupled to a camera and an endoscope; and,

FIG. 10 is a proximal perspective view of the coupler, from the opposite side shown in FIG. 9, shown coupled to a camera and an endoscope.

The features shown in broken lines in the drawings depict environmental subject matter and are for illustrative purposes only; the broken lines form no part of the claimed design.

1 Claim, 10 Drawing Sheets
